Primary Examiner — Paula Allen Greene(74) *Attorney, Agent, or Firm* — Plumsea Law Group, LLC(57) **CLAIM**

The ornamental design for an element of a loudspeaker, as shown and described.

DESCRIPTION

FIG. 1 is a front elevational view of an element of a loudspeaker showing the new design; and,

FIG. 2 is an enlarged view of the portion 2 denoted in FIG. 1.

The broken lines depict environment that forms no part of the claimed design. The dot-dash-dot lines depict the boundary that is for illustrative purposes only and forms no part of the claimed design.

1 Claim, 2 Drawing Sheets(56)
